(Cl. D33—14)

To all whom it may concern:

Be it known that I, Walter Clifford Cunningham, a subject of the King of England, residing at 43 Kings Road, Horsham, Sussex, England, have invented a new, original, and ornamental Design for Racking Table, of which the following is a specification, reference being had to the accompanying drawings, forming part thereof, in which:

Fig. 1 is a view in front elevation of the racking table, showing my new design.

Fig. 2 is a perspective view of my racking table.

Fig. 3 is a view thereof in rear elevation, and
Fig. 4 is a top plan view thereof.

I claim:

The ornamental design for a racking table, as shown.

WALTER CLIFFORD CUNNINGHAM.
